UNITED STATES PATENT OFFICE.

JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

LOOM HARNESS.

Application filed April 20, 1923. Serial No. 633,360.

My invention relates to loom harness, and it relates more particularly to the construction and arrangement of the heddles in the heddle frames for controlling the warp ends for the purpose of forming successive sheds of the warp during the operation of the loom.

The object of my invention is to provide an improved form of construction and arrangement of the heddles in the heddle frames which is particularly adaptable for close installations for weaving fine fabrics, and whereby the warp ends controlled by adjacent frames will more freely pass the eyes of the heddles during the reciprocation of the frames for the purpose of forming the sheds, thereby minimizing, to a large extent, breakage of the warp ends.

While it should be understood that the underlying principle of my present invention may be used in connection with various types of heddles, the invention will, however, find its greatest usefulness in connection with that type of metallic heddles as distinguished from cotton or thread harness which are formed from thin flat strips of metal or wire, having the warp eyes formed in the central portions thereof by slitting the metal of the strip and expanding the same to form the eye through which the warp end passes.

Heretofore, it has been recognized by those skilled in the art that a great deal of breakage of the warp ends occurs by reason of the resistance which occurs during the reciprocation of the various heddle frames in the loom, at the particular instant when the threads controlled by one of the frames passes the warp eyes of the heddles mounted in another of the heddle frames, this occurring particularly in the weaving of fine fabrics where the installation of the heddles in the frames is close, and where the warp is necessarily fine, and therefore more easily broken.

To overcome the above mentioned difficulty, in some instances there were provided a plurality of sets of heddle frames, each set being operated in unison to control one set of the warp ends, which was a more or less clumsy expedient, and which led to the subsequent development of the mounting of a plurality of sets of heddles in a single frame,

arranged in a plurality of separated vertical planes. Another expedient subsequently developed comprised the provision of heddles off-set out of the plane of the supporting bars, and arranged with the off-set portions alternatively to one side and another, so as to cause the warp eyes to lie in separated vertical planes. These expedients, however, have been found insufficient to fully accomplish the desired purpose, particularly for weaving fine fabrics, and my present invention contemplates a still further advance in the art, as will be hereinafter more fully set forth.

While there is shown and described in the present application one species of my present invention, and the same is herein shown as embodied in various modifications of said species, I have also shown and described in a companion application, filed herewith, another species and the manner of embodying the same in various modifications thereof. It should, however, be understood that my invention is susceptible of embodiment in a variety of other species and modifications thereof, as will be readily apparent to those skilled in the art upon a proper understanding of the underlying principle of my present invention.

The nature and characteristic features of my present invention will be more readily understood from the following description, taken in connection with the accompanying drawings forming part hereof, in which:

Figure 1 is an elevational view of a heddle frame having heddles, constructed and arranged in such manner as to embody the main features of my present invention, mounted therein;

Fig. 2 is a vertical sectional view thereof;

Fig. 3 is a sectional view, similar to Fig. 2, but showing a modified form of construction and arrangement of the heddles;

Fig. 4 is a fragmentary elevational view illustrating the arrangement of the heddles shown in Fig. 3; and

Fig. 5 is a sectional view, similar to Figs. 2 and 3, but showing another modified form of construction and arrangement of the heddles.

Referring to the drawings, the heddle frame there shown consists of the top and bottom bars 6, connected at their ends by

means of the side strips 7. Extending from end to end of the heddle frame, and arranged near the top and bottom bars 6 in the usual manner, are the heddle bars 8 upon which the heddles are mounted.

Referring now more particularly to Figs. 1 and 2 of the drawings, the heddles which are mounted upon and supported by the bars 8 are provided in two sets, 9 and 10, respectively. The heddles 9 and 10 of each set are provided with warp controlling eyes in the central portions thereof, which warp eyes may be of any preferred conformation. The relative location of the warp eyes 11 of the heddles 9 with respect to the warp eyes 12 of the heddles 10, when the same are mounted in the frame, is an important feature of the present invention. The warp eyes 11 of the heddles 9 are longitudinally located therein, and the warp eyes 12 of the heddles 10 are longitudinally located therein, at such positions, respectively, that the warp eyes of the set of heddles 9 will lie in a horizontal plane different from that of the warp eyes 12 of the set of heddles 10.

The heddles are mounted upon the supporting bars by first placing thereon a heddle 9 of one set, then a heddle 10 of the other set, then another heddle 9 of the first mentioned set, then another heddle 10 of the other set, and so on alternately throughout the frame.

In the modification of the invention shown in Figs. 3 and 4 of the drawings, there are provided two pairs of sets of heddles, making in all four sets of heddles differently arranged as to the positions of their respective warp eyes, and preferably arranged in series of one of each set. The heddles 15 and 16 of one pair of sets are off-set, as at 17, so as to cause the central portions of said heddles to lie to one side of the vertical plane of the supporting bars 8, while the heddles 18 and 19 of the other pair of sets are similarly off-set, as at 20, but so as to cause the central portions of those heddles to lie to the other side of the vertical plane of the supporting bars 8.

In this form of the invention (shown in Figs. 3 and 4), the warp eyes 21 of the heddles 15 are longitudinally located upon the heddles 15 at such position that all of the warp eyes of the set of heddles 15 will lie in a horizontal plane different from that of the warp eyes 22 of the set of heddles 16, and likewise the warp eyes 23 of the set of heddles 18 are longitudinally located upon the heddles 18 at such position that all of said warp eyes 23 of the set of heddles 18 will lie in a horizontal plane different from that of the warp eyes 24 of the set of heddles 19. By this arrangement, the heddles will be preferably mounted upon the supporting bars by first placing thereon a heddle 15 of one set, then a heddle 16 of another set, then

a heddle 18 of still another set, then a heddle 19 of still another set, and so on in similar series throughout the frame.

In Fig. 5 of the drawings, there is shown another embodiment of the invention, where-in the use of off-set heddles may be dispensed with, and which is particularly adaptable to extremely close installations. In this instance there are provided, at the top and bottom of the frame, two or more of the heddle supporting bars 8, and the heddles in this form of the invention may be substantially straight throughout their longitudinal extent, similar to those illustrated in Figs. 1 and 2 of the drawings, there being mounted, on each pair of the supporting bars 8, heddles 9 and 10 in which the eyes 11 and 12 thereof, respectively, will be located alternately above and below each other.

It will be seen that in each of the foregoing arrangements there is provided, in a single harness frame, a plurality of sets of heddles, the warp eyes of each set of which will lie in different horizontal planes, and by this arrangement, as the frames are reciprocated during the operation of the loom, a greater freedom for the passage of the warp ends, controlled by the adjacent frames, will be afforded, in that the warp eyes being located in a plurality of different horizontal planes, resistance to the passage of the warp ends, which are controlled by the other frames, will be greatly minimized, and in this manner breakage of the warp ends, due to the strain which ordinarily occurs at this point, will be reduced to a minimum.

It should also be understood that the various forms illustrated are, to a certain extent, suggestive merely, and that a variety of other forms or embodiments of the invention will readily occur to those skilled in the art.

Having thus described the nature and characteristic features of my invention, what I claim as new and desire to secure by Letters Patent is:

1. In a loom harness, a harness frame, heddle supporting bars carried thereby, and individual heddles formed of thin flat metal or wire mounted upon said supporting bars in a plurality of sets, the heddles of one set having warp controlling eyes at certain longitudinal locations and the heddles of another set having warp controlling eyes at different longitudinal locations, whereby the warp controlling eyes of one set of heddles are in one horizontal plane and the warp controlling eyes of another set are in another horizontal plane, and the eye portions of one of said sets of heddles being in the same vertical plane as the eye portions of another set of heddles.

2. In a loom harness, a harness frame, heddle supporting bars carried thereby, and individual heddles formed of thin flat metal

or wire mounted upon said supporting bars in a plurality of sets, the heddles of one set having warp controlling eyes at certain longitudinal locations and the heddles of another set having warp controlling eyes at different longitudinal locations, whereby the warp controlling eyes of one set of heddles are in one horizontal plane and the warp controlling eyes of another set are in another 10 horizontal plane, and the eye portions of one of said sets of heddles being in the same vertical plane as the eye portions of another set of heddles, and the heddles being arranged upon the supporting bars in successive series of one of each set.

3. In a loom harness, a harness frame, heddle supporting bars carried thereby, and individual metal heddles mounted upon said supporting bars in a plurality of groups of 20 sets having warp controlling eyes located in their central portions, the central portions of one group of sets of said heddles being located in one vertical plane and the central portions of another group of sets being located in another vertical plane, the warp controlling eyes of one set of said heddles in each group being arranged in one horizontal plane and the warp controlling eyes of another set in said group being located in another horizontal plane.

4. In a loom harness, a harness frame, heddle supporting bars carried thereby, and individual heddles formed of thin flat metal or wire mounted upon said supporting bars in a plurality of groups of sets having warp controlling eyes located in their central portions, the central portions of one group of sets of said heddles being located in one vertical plane and the central portions of another group of sets being located in another vertical plane, the warp controlling eyes of one set of said heddles in each group being arranged in one horizontal plane and the warp controlling eyes of another set in said group being located in another horizontal plane.

5. In a loom harness, a harness frame, heddle supporting bars carried thereby, and individual metal heddles mounted upon said supporting bars in a plurality of groups of sets having warp controlling eyes located in their central portions, the central portions of one group of sets of said heddles being located in one vertical plane and the central portions of another group of sets being located in another vertical plane, the warp controlling eyes of one set of said heddles in each group being arranged in one horizontal plane and the warp controlling eyes of another set in said group being located in another horizontal plane.

6. In a loom harness, a harness frame, heddle supporting bars carried thereby, and

individual heddles formed of thin flat metal or wire mounted upon said supporting bars in a plurality of groups of sets having warp controlling eyes located in their central portions, the central portions of one group of 70 sets of said heddles being located in one vertical plane and the central portions of another group of sets being located in another vertical plane, the warp controlling eyes of one set of said heddles in each group being 75 arranged in one horizontal plane and the warp controlling eyes of another set in said group being located in another horizontal plane, the heddles being arranged upon the supporting bars in successive series of 80 one of each set of each group.

7. In a loom harness, a harness frame, heddle supporting bars carried thereby, and individual heddles formed of thin flat metal or wire mounted upon said supporting bars 85 in a plurality of groups of sets having warp controlling eyes located in their central portions, the central portions of one group of sets of said heddles being off-set to one side of the vertical plane of the supporting bars 90 and the central portions of another group of sets being off-set to the other side of the vertical plane of the supporting bars, the warp controlling eyes of one set of said heddles in each group being arranged in one 95 horizontal plane and the warp controlling eyes of another set in said group being located in another horizontal plane.

8. In a loom harness, a harness frame, heddle supporting bars carried thereby, and individual metal heddles mounted upon said supporting bars in a plurality of groups of sets having warp controlling eyes located in their central portions, the central portions of one group of sets of said heddles being 100 off-set to one side of the vertical plane of the supporting bars and the central portions of another group of sets being off-set to the other side of the vertical plane of the supporting bars, the warp controlling eyes of one set of said heddles in each group being 105 arranged in one horizontal plane and the warp controlling eyes of another set in said group being located in another horizontal plane.

9. In a loom harness, a harness frame, heddle supporting bars carried thereby, and individual heddles formed of thin flat metal 110 or wire mounted upon said supporting bars in a plurality of groups of sets having warp controlling eyes located in their central portions, the central portions of one group of sets of said heddles being off-set to one side 115 of the vertical plane of the supporting bars and the central portions of another group of sets being off-set to the other side of the vertical plane of the supporting bars, the warp controlling eyes of one set of said heddles in each group being 120 arranged in one horizontal plane and the warp controlling eyes of another set in said group being located in another horizontal plane.

10. In a loom harness, a harness frame, heddle supporting bars carried thereby, and

dles in each group being arranged in one horizontal plane and the warp controlling eyes of another set in said group being located in another horizontal plane, and the heddles being arranged upon the supporting bars in successive series of one of each set of each group.

10. In a loom harness, a harness frame, heddle supporting bars carried thereby, and individual metal heddles mounted upon said supporting bars in a plurality of groups of sets having warp controlling eyes located in their central portions, the central portions of one group of sets of said heddles

being off-set to one side of the vertical plane 15 of the supporting bars and the central portions of another group of sets being off-set to the other side of the vertical plane of the supporting bars, the warp controlling eyes of one set of said heddles in each group being arranged in one horizontal plane and the warp controlling eyes of another set in said group being located in another horizontal plane.

In testimony whereof, I have hereunto 25 signed my name.

JACOB KAUFMANN.
